(57) **CLAIM**

The ornamental design for a storage basket, as shown and described.

DESCRIPTION

FIG. 1 is a front, top perspective view of a storage basket, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view of the storage basket, shown in an alternate configuration; and,

FIG. 10 is a rear, bottom perspective view thereof.

The broken lines in the figures illustrate portions of the storage basket that form no part of the claimed design.

1 Claim, 10 Drawing Sheets
